Atty.

UNITED STATES PATENT OFFICE.

ELSA BÜNZLI, OF ZURICH, SWITZERLAND.

PURSE.

Application filed March 10, 1923. Serial No. 624,287.

To all whom it may concern:

Be it known that I, ELSA BÜNZLI, a citizen of Switzerland, residing at Zurich, Switzerland, have invented a new and useful Purse, of which the following is a specification.

The present invention has reference to improvements in purses and relates more specifically to a purse of the box type, which is provided with a plurality of independently operable drawers, all of which are securable in their innermost, that is closed, position by the shut purse cover, one or more of the drawers being spring-influenced to be pushed forward to some extent for ready access upon the cover being opened.

In order to make my invention more readily understood, I will now describe it in detail in connection with the accompanying drawing, in which Fig. 1 is a perspective top view of the box purse with opened cover; Fig. 2 is a similar view with the interior closing flaps lifted to expose the several compartments with their drawers, and Fig. 25 shows two of the drawers pushed out.

The box purse may be of any suitable rigid material, for instance aluminum for its light weight and untarnishable character, and it comprises the body part 1 and the circumferentially downwardly flanged cover part 2 hinged to the member 1 along their rear longitudinal edges. The body is subdivided into a plurality of compartments, for instance four, as shown by way of example, and in each compartment except in IV, there is provided a slideable drawer I, II and III respectively. Two flat cover flaps 3 and 4 are hinged to the body, each flap covering several compartments, and knobs 5 thereon facilitate handling the flaps. Between the rear walls of the body 1 and the drawers I and II are shown springs 6 which tend to push forward these drawers, when the lip or flange 12 of the cover 2, which normally that is to say in the closed state of the purse, overhangs the upper front edge of the drawers, on opening of the cover frees the drawers.

The compartment IV, for instance, may be used to contain gold coins, and the drawers I, II and III respectively paper money, silver and other coins. The cover flap 4

on top is designed to serve as writing surface direct or as base for writing pad, and a writing stylus 7 is suitably mounted on the underside of the box cover for ready access, as shown in Fig. 1. The pocket 8, preferably of the bellows type, may be used to hold visiting cards, stamps, or the like. To prevent the contents of the several compartments from being spilled when the purse is opened in somewhat forwardly inclined position, there is provided a narrow guard strip 9 of preferably reticulated material across the front width of the box. 65 The drawers may be provided with a sound-deadening lining 10.

What I claim is:—

1. In a box-purse of the character set forth, the combination of a body part, a cover part hinged to the rear edge thereof, a plurality of forwardly opening drawers in said body part, a guard extending across the forward edge of the body and over the drawers, and said cover part adapted to prevent relative movement of said drawers in the closed position of the cover.

2. In a box-purse of the character set forth, the combination of a body part presenting compartments, a cover part including a depending lip hinged to said body part, drawers in said compartments, said cover lip partly overhanging the front wall of said drawers in the closed position of said cover and said drawers, and constantly tensioned means interposed between said body part and said drawers for propelling said drawers in a forward direction on their release upon the said cover being lifted, said means holding the drawers tensioned 85 against the overhanging cover lip and thereby tending to hold the cover closed through frictional contact.

3. In a box-purse of the character set forth, in combination, a body member presenting compartments, a cover member, presenting an overhanging longitudinal front lip and hinged to said body along its longitudinal rear edge, flaps interposed between said cover and said compartments and 100 also hinged to said rear edge for opening up into the open cover, a receptacle mounted on the inside of said cover to be concealed by said flaps and the latter are in open

position, drawers in the compartments opening towards the front, spring means interposed between the rear walls of said body and of at least one of said drawers, sound-deadening lining in said drawers, a guard member across the upper front width of said body, and the overhanging

cover lip adapted to coact with the upper edges of the drawers in the innermost position of the latter for preventing their relative forward movement in the closed position of said cover. ¹⁰

ELSA BÜNZLI.
